UNITED STATES PATENT OFFICE.

HARRY T. PHILPOTT, OF BROOKS, ALBERTA, CANADA, ASSIGNOR OF ONE-HALF TO
C. A. SPARROW, OF BROOKS, CANADA.

WINDOW LIFT AND FASTENER.

Application filed May 16, 1924. Serial No. 713,813.

To all whom it may concern:

Be it known that I, HARRY T. PHILPOTT, a British subject, residing at Brooks, in the Province of Alberta and Dominion of Canada, have invented new and useful Improvements in Window Lifts and Fasteners, of which the following is a specification.

This invention relates to builders' hardware and has for its object the provision of a novel combined window lift and securing device or catch which will hold the window in closed position and prevent it from being opened from the outside by an unauthorized person, the device automatically fastening when the window is closed.

An important object is the provision of a device of this character which is constructed from an extremely small number of parts and which will therefore be simple and inexpensive to manufacture, easy to install and at the same time positive in action, efficient and durable in service and a general improvement in the art.

With the above and other objects and advantages in view the invention consists in the details of construction to be hereinafter more fully described and claimed and illustrated in the accompanying drawings, in which.

Figure 1 is a front elevation of the device, Figure 2 is a vertical section therethrough showing it associated with a window,

Figure 3 is an end elevation,

Figure 4 is a detail view of the keeper.

Referring more particularly to the drawings the numeral 10 designates the body of the device which is formed from a single piece of sheet metal cut and bent to the shape indicated so as to provide a compartment 11 defined by the sides 12 which terminate in attaching portions 13 which are provided with holes for the passage of nails, screws or other securing elements. The upper extremity of the body 10 is formed with an elongated reflexly curved tongue 14 which constitutes the handle or lift by means of which the window A may be raised. Near its upper and lower ends the front of the body is formed with slots 15 and 16 respectively.

The device further includes a catch which is formed from an elongated strip 17 which is bowed or curved in shape and which has its upper end passed through the upper slot 15. The lower end of this strip is

passed through the slot 16 and is bent into angular shape to define a shoulder 19 and an inclined end 20 leading thereto. Riveted at 21 on the inside of the front portion of the body is a leaf spring 22 which bears 60 against the lower end portion of the catch for normally holding it in its forwardmost position.

Mounted on the sill B over a suitable recess 23 therein, is a keeper plate 24 having 65 an opening 25 for the passage of the angular end of the catch.

Assuming that the device has been constructed and installed as above described, it is apparent that when the window is 70 closed the engagement of the inclined end 20 of the catch with the edge of the opening 25 will cause the strip 17 to move rearwardly or toward the window sash until the shoulder 19 snaps under the plate or 75 keeper 24. The spring 25 operates to hold this catch in its fastened position. To open the window it is necessary to push upon the curved strip 17 or catch so as to disengage the angular end from the keeper, 80 whereupon the window may be lifted by pulling upon the handle or lift 14.

From the foregoing description and a study of the drawings it will be apparent that I have thus provided an extremely 85 simple, inexpensive and yet highly efficient device for the purpose specified which will be neat and attractive in appearance and which is almost impossible to get out 90 of order.

While I have shown and described the preferred embodiment of my invention it is of course to be understood that I reserve the right to make such changes in the form, construction and arrangement of parts as 95 will not depart from the spirit of the invention or the scope of the subjoined claims.

Having thus described my invention I claim:

1. A combined window lift and catch, 100 comprising a body member mounted upon a window sash and formed to provide a compartment, the upper end of said body being formed with a handle, the front of the body being provided near its upper and lower ends with slots, a catch formed as a curved strip located in front of the body with its ends passing through said slots, the upper end being secured and the lower end free, 105 said lower end having a shoulder and an 110

inclined surface leading thereto, a spring urging said curved strip outwardly, in combination with a keeper plate mounted upon the sill and having an opening for the passage of the angular end of the catch.

2. A device of the character described comprising a body formed from a single piece of sheet metal having angularly extending parallel sides defining a compartment, said sides terminating in attaching portions, the upper end of the body terminating in an elongated reflexly curved tongtie constituting a lift, said body being provided in its front with upper and lower slots, a curved catch extending through both slots and secured above the upper one, the lower end of the catch being formed to provide a shoulder and an inclined terminal portion leading thereto, and a keeper plate having an opening for the passage of said angular end.

3. A device of the character described comprising a body formed as a plate adapted to be mounted upon the sash rail of a

window to cover a recess formed therein, a keeper plate let into the window frame in horizontal position and having an opening therein, the upper end of said first named plate being formed as a lift, a curved catch member located in front of the body formed at its upper end with a reduced tongue, the upper portion of the body having a slot therein for the passage of said tongue, the lower end of said catch member being formed with an angularly extending shoulder adapted for engagement beneath the keeper plate and terminating in an inclined extension, a spring secured upon the rear side of the body and bearing against the lower end of the catch member and a securing member passing through the intermediate portion of the body and into the sash rail, said securing member further acting as a guide for the sash and spring member during movement thereof.

In testimony whereof I affix my signature.

HARRY T. PHILPOTT.
